PIVOTALLY MOUNTED CLOSET DISPOSAL
William S. Miller, Jr., 2873 Adams Ave.,
San Diego, Calif. 92116
Filed Sept. 1, 1964, Ser. No. 393,626
2 Claims. (Cl. 4-8)

The present invention relates to a disposal which is adapted to be wheeled about, and more particularly to a disposal for draining offal from house trailers.

The disposal of the present invention comprises a cart having a frame and preferably two wheels. An assembly, including a container and two flexible tubes, is pivotally carried by the frame of the cart. The pivotal connection is above the center of gravity of the assembly. One of the tubes is connected to the bottom of the container and the other tube is connected adjacent the top of the container.

The free end of the tube which is connected to the bottom of the container is adapted to be connected with, for example, a sewage tank of a house trailer for draining the tank, and that tube provides for draining the container of the disposal. The other tube is connectable with a water faucet for cleansing the interior of the container.

Other features and the advantages of the present invention will be apparent from the following description, reference being had to the accompanying drawing, wherein a preferred embodiment of the invention is illustrated.

In the drawing:

FIG. 1 is a perspective view of the disposal, shown in an upright position, parts thereof being broken away to show details of construction; and

FIG. 2 is a left side view of the disposal, showing how the contents of the container is drained into a toilet bowl, the bowl being shown in phantom.

Referring more in detail to the drawing, the disposal is shown at 20 and includes a cart 22 and an assembly 24, the assembly including principally a container 26 and two flexible tubes 28 and 30. The container is pivotally supported by the cart 22.

The cart includes an inverted U-shaped frame 32, including upright legs 34 and 36, the upper ends of which are connected by a yoke 38. An axle 40 is attached to the lower end of the legs, and wheels 42 are mounted on the axle.

The container 26 is formed preferably of substantially rigid plastic and is relatively thin with respect to its width and height. The container is provided with flanges 44 on opposite sides thereof. Brackets 46 are attached to each of these flanges as by rivets 48, and these flanges are in turn connected by pins 50 to the legs 34 and 36.

One of the tubes 28 is clamped to the bottom neck 52 of the container 26 by clamp 54. A collar 55 is slidably mounted on the tube 28 and pivotally carries a hook 56. This hook can be received by an eye 58 at the top of the container for supporting the free end of the tube. The free end of the tube 28 is provided with a plug 60, which, when removed, permits the free end of the tube 28 to be connected, for example, with a sewage tank of a house trailer.

The tube 30 is connected to the container 26 by a neck 62 on the container. The free end of the tube is provided with a socket coupling 64 for connecting the tube with a water faucet. The tube 30, when not in use, is supported on the container by a hook 66, the latter being disposed adjacent the top of the container.

The pivotal connection for the assembly 24 with the cart 22 is above the center of gravity whereby, when the container is pivotally supported by the cart, the end of

2

the container 26 to which the tube 28 is held by the clamp 54 is always lower than the opposite end. The flanges or stops 44 on the container are in abuttable relationship with the legs 34 and 36 of the frame, whereby, when the disposal is wheeled about, swinging, i. e., clockwise movement of the assembly, as viewed in FIG. 1, is prevented while the disposal is being wheeled in a normal manner.

In operating the disposal, the entire disposal is laid flat upon the floor or earth. The plug 60 is then removed from the free end of the tube 28 and the free end of the tube is then connected with the disposal tank of the trailer. Such sewage tanks are usually provided with a valve at the outlet. This valve is then opened and the sewage flows into the container 26. After draining the sewage tank, or after substantially filling the container 26, the valve on the tank is closed and the tube is removed from the outlet of the tank; the plug 60 is then reinserted in the free end of the tube. The tube is then hung by the hook 56 in the eye 58.

The disposal is then wheeled, for example, to adjacent a toilet bowl, shown in phantom at 68. The hook 56 is then slid to a position as shown in FIG. 2 and connected over the top of the toilet bowl for holding the free end of the tube 28 in position on the toilet bowl. After the plug 60 is removed, the top end of the frame is then lifted and the container is tilted to raise the entire container above the top of the toilet bowl whereby the contents of the container is drained into the toilet bowl.

The container 26 can be flushed to cleanse the same by attaching the coupling 64 with a water faucet, when the disposal is in an upright position, the water draining from the lower tube 28. Preferably, at this time the free end of the tube 28 is below the container 26.

Thus, it is apparent from the foregoing that there has been provided a disposal which is simple in construction, inexpensive and simple to operate.

While the form of embodiment herein shown and described, constitutes preferred form, it is to be understood that other forms may be adopted falling within the scope of the claims that follow:

I claim:

1. A disposal, comprising in combination:

(A) a cart including:

(1) a frame;

(2) wheel means for supporting the frame;

(B) a container;

(C) a plurality of flexible tubes connected with the container to form an assembly therewith;

(D) means for pivotally connecting the container with the frame, said pivotal means being disposed above the center of gravity of the assembly;

(E) and a stop on the container engageable with the frame for preventing the swinging movement of the container when the disposal is being wheeled in a normal manner.

2. A combination as defined in claim 1, characterized in that one of the tubes is connected to the bottom of the container, and further characterized to include:

(F) a hook carried by said one tube for removably attaching said tube to the bowl of a toilet.
